UNITED STATES PATENT OFFICE.

ALFRED R. ANDERSEN, OF ROCK SPRINGS, WYOMING.

ANTISKIDDING DEVICE.

1,415,289.

Specification of Letters Patent. Patented May 9, 1922.

Application filed February 23, 1922. Serial No. 538,716.

To all whom it may concern:

Be it known that I, ALFRED R. ANDERSEN, a citizen of the United States, residing at Rock Springs, in the county of Sweetwater and State of Wyoming, have invented certain new and useful Improvements in Anti-skidding Devices, of which the following is a specification, reference being had to the accompanying drawings.

10 This invention relates to certain improvements in anti-skidding devices and has relation more particularly to a device of this general character especially designed and adapted for use in connection with wheels of 15 motor driven vehicles and it is an object of the invention to provide a novel and improved device of this character which, when applied, will operate effectively to prevent skidding and also slippage.

20 Another object of the invention is to provide a device of this general character having novel and improved means whereby the same may be quickly applied and easily removed and also effectively maintained in 25 applied position.

The invention consists in the details of 30 construction and in the combination and arrangement of the several parts of my improved anti-skidding device whereby certain important advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:

40 Figure 1 is a fragmentary view in side elevation illustrating an anti-skidding device constructed in accordance with an embodiment of my invention and in applied position;

45 Figure 2 is an enlarged sectional view taken substantially on the line 2—2 of Figure 1;

50 Figure 3 is a view in top plan of one of the tread units as herein disclosed;

Figure 4 is a view in top plan of the pulley and mounting therefor associated with each of the side members;

55 Figure 5 is a view in side elevation of the structure illustrated in Figure 4; and

Figure 6 is a sectional view taken through the holding sleeves.

As disclosed in the accompanying drawings, C denote side chains and each of said chains has secured to an end thereof a substantially U-shaped member M, one side arm 1 of which is hingedly mounted, as at 2, so that the same may be readily swung into or out of operative position. 3 denotes a pulley mounted upon the shaft 4, said shaft 65 having its extremities mounted in the free end portions of the side arms 1 and 1^a of the member M, the hinge connection 2 of the arm 1 permitting said arm to be adjusted to facilitate the proper application 70 of the pulley 3 in working position. The outer faces of the arms 1 and 1^a are provided with the spring hooks 5 which engage through the extremities of the shaft 4 whereby said shaft is effectively held in working 75 position.

The opposite end portion of the chain C has secured thereto an extremity of a cable or kindred flexible member A. This member is threaded through a sleeve 6 and in 80 applying the complete device to the tire of the wheel, said cable is passed around the pulley 3 and extended through a second sleeve 7, said sleeve 7 being connected to the sleeve 6. Threaded through a wall of 85 each of the sleeves 6 and 7 is a set or binding screw 8 which is adapted to have clamping action upon the portions of the cable A extending therethrough whereby the side chain C is effectively maintained in applied 90 position, the use of the sleeves 6 and 7 and the associated binding screws 8 affording a double securing means to assure the proper maintenance of the side chain C in applied position.

95 Connecting the side chains at predetermined spaced points therealong are the tread units B. Each of the units B embodies a plate P of a length and of such curvature to straddle the tread portion of the tire T. Extending longitudinally of the plate P at its transverse center is an outstanding rib or flange 9 and extending transversely across the plate at substantially its longitudinal center is a second rib or flange 100 10. The ribs or flanges 9 and 10 operate effectively to prevent skidding or slippage. The opposite end portions of each of the plates P is provided with an extension 105 11 returned upwardly to provide the barrels 12. 110

Freely disposed through each of the barrels 12 is the intermediate or base portion 14 of a substantially U-shaped member D. The free extremities of the side members 15 of the member D are formed into the eyes 16. The eyes 16 have loosely disposed there-through the intermediate or base portion 17 of a substantially U-shaped member E. The free extremities of the side members 18 of the member E are provided with the hook members 19 which are engaged with certain of the links 20 of the side chain C.

By having a pair of members D and E associated with each end portion of a plate P, it is assured that the plate P will not effect a rim cut and which is further prevented in view of the fact that the plate P is only of a length to straddle the tread portion of the plate P.

20 The members D and E also serve effectively to maintain the plates P firmly in working position and at all times preventing said plates from turning over and thereby being liable to cut the tire.

25 The construction of the plates P is also such to prevent the same becoming clogged with mud, snow, ice and the like so that said plates are at all times in condition to effect the best gripping action on the roadway.

30 From the foregoing description it is thought to be obvious that an anti-skidding device constructed in accordance with my invention is particularly well adapted for use by reason of the convenience and facility 35 with which it may be assembled and oper-

ated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A device of the class described comprising a pair of side members, tread units interposed between and connected with said side members, a flexible member secured to an extremity of each of said side members, a substantially U-shaped member carried by the opposite end portion of said side member, one of the side arms of said last named member having swinging movement, a shaft supported by the outer extremities of the side arms of the last named member, a pulley mounted upon said shaft between the arms, the flexible member at the opposite extremity of said side member being disposed around the pulley, spring hooks carried by the side arms of the last named member and engageable with the extremities of the shaft to hold the shaft and pulley in applied position, and means connecting the portion of the flexible member in advance of the pulley and the portion of the flexible member outwardly of the pulley.

In testimony whereof I hereunto affix my signature.

ALFRED R. ANDERSEN.
